US00D974875S

(12) **United States Design Patent** (10) Patent No.: **US D974,875 S**
(45) Date of Patent: **** Jan. 10, 2023**

(54) **MOUNTING COMPONENT**

- (71) Applicant: **Shenzhen ShunFa Optoelectronic Co., LTD**, Shenzhen (CN)
- (72) Inventor: **Huayong Ou**, Shenzhen (CN)
- (73) Assignee: **Shenzhen ShunFa Optoelectronic Co., LTD**, Shenzhen (CN)

(**) Term: **15 Years**

(21) Appl. No.: **29/813,481**

(22) Filed: **Oct. 29, 2021**

(51) LOC (14) Cl. **08-08**

(52) U.S. Cl. **D8/349**
USPC ....

(57) **CLAIM**

The ornamental design for a mounting component, as shown and described.

DESCRIPTION

FIG. 1 is a perspective view of a mounting component showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets

FIG. 1

FIG. 2

FIG. 3

FIG. 4

FIG. 5

FIG. 6

FIG. 7
